UNITED STATES PATENT OFFICE

140,248

DESIGN FOR A CIGAR BOX COUNTER DISPLAY

Robert B. Wemyss, Louisville, Ky.

Application October 30, 1944, Serial No. 116,054

Term of patent 7 years

(Cl. D80—9)

To all whom it may concern:

Be it known that Robert B. Wemyss, a citizen of the United States, residing in Louisville, county of Jefferson, State of Kentucky, has invented a new, original, and ornamental Design for a Cigar Box Counter Display, of which the following is a specification, reference being had to the accompanying drawing forming part thereof.

The figure is a perspective view of a cigar box counter display showing my new design.

I claim:

The ornamental design for a cigar box counter display, substantially as shown.

ROBERT B. WEMYSS.
